MASCHINENFABRIK, AKTIENGESELLSCHAFT, OF CHEMNITZ, GERMANY

STOCKING AND METHOD OF KNITTING SAME ON FLAT KNITTING MACHINES

Application filed August 1, 1931. Serial No. 554,548, and in Germany August 5, 1930.

My invention relates to stockings and to the method of knitting same on flat knitting machines.

The stocking according to my invention 5 has a pair of rows of widened selvedge loops to be sewed at the extended heel portions, and narrowing lines which start from the rear upper end of the heel as in a pointed high heel, and extend toward the ankle, or 10 to a point below the ankle, at an inclined angle and on the same wale.

My method is based on the old method in which the heel and foot portions are 15 knitted at the same time and the selvedge loops to be sewed are widened outwardly for increasing the width of the heel portions. In this old method, however, it is not possible to obtain narrowing lines of 20 the pointed high heel type but only narrow lines which start from the region of the ankle.

According to my invention I obtain the narrowing lines of a pointed high heel, i. e., lines starting from the upper rear end of 25 the heel and following the same wales in the direction toward the sole. Such pointed high heel narrowing lines could be knitted on a single machine heretofore only by narrowing originally wider rows but this presents the difficulties that the machine must 30 be arrested when starting for these originally wider rows and that the originally wider rows must be drawn off separately.

My novel method not only eliminates 35 these difficulties but in addition presents the advantage that the widened portion of the heel with pointed high heel narrowing lines is knitted from the leg in a form corresponding to the shape of the foot.

40 In my method, after finishing the leg the widening of the heel is effected by not only widening selvedge loops to be sewed in one row of loops but also transferring inwardly heel loops in the same row and at the same 45 time, the number of which transferred heel loops is increased for each subsequent row. Widening and transferring within a row 50 of loops is effected at the same time in both heel portions while selvedge loops to be sewed are formed at one end of a row in

the heel portion, heel loops are formed and transferred inwardly at the opposite end of the row, the transferring of the loops not interfering with the selvedge loops to be sewed, and thereupon the selvedge loops at 55 this end of the row are formed by widening. It will be understood that in this manner the selvedge loops to be sewed are maintained in their position on the selvedge at both ends of each row while the loops intermediate the selvedge loops are transferred inwardly.

In the drawings affixed to this specification and forming part thereof a heel portion, the stages of knitting a row of loops, 65 and a portion of a finished stocking according to my invention are illustrated diagrammatically by way of example.

In the drawings Fig. 1 is a diagram of the loops in the 70 heel portions,

Figs. 2 to 5 illustrate the stages of knitting a row of loops, and

Fig. 6 shows a narrowing line of the finished stocking. 75

When the leg has been finished as far as the line $a-a$ in Fig. 1, a selvedge loop is formed by widening at both ends of a row, the next row is sunk, and the tickler (not shown) is moved from the right to the left 80 in Fig. 2. At the right-hand end of the row it transfers the three selvedge loops on the needles 14, 15 and 16 to the needles 13, 14 and 15, the needle 13 having two loops, and the needle 16 being empty. The selvedge loop on the needle 17 is not transferred inwardly. At the other end of the row the tickler widens by transferring the loops from the needles 2 and 3 to the needles 1 and 2 in outward direction while the needle 3 is empty. The tickler now returns, Fig. 3, for 85 performing the next course of the same row without influencing the row at its left-hand end, and without interfering with the inwardly transferred loops on the needles 13 and 14, but transferring the loop on needle 15 to needle 16 and transferring the loop on the needle 17 to the needle 18 as the outer selvedge loop. The tickler now returns and 90 starts afresh from the left for the next row, 95 100

- Fig. 4, transferring the loops on needles 3, 4, 5, 6 to needles 4, 5, 6, 7 in inward direction at the left and transferring the loop from needle 16 to needle 17 at the right.
- 5 Upon the next return of the tickler for performing the next course on the same row from the right to the left, Fig. 5, the selvedge loops on the needles 17 and 18 at the right are not interfered with but the loop 10 from the needle 2 is transferred to the needle 1, and finally the loop from the needle 3 is transferred to the needle 2, Fig. 2, obtaining two selvedge loops at the left as well as at the right-hand end of the row.
- 15 When the desired form of the heel has been knitted as described with reference to Figs. 2 to 5, a given number of rows are knitted by covering without narrowing from *b*—*b* to *c*—*c* by transferring loops inwardly as described but without interfering with the selvedge loops, whereupon the 20 foot is narrowed in the usual manner from *c*—*c* to *d*—*d*, and the instep gusset may then be knitted.
- 25 The lines *a*—*a* etc., in Fig. 1 are shown at the finished stocking in Fig. 6. From *a*—*a* where the leg is finished, to *c*—*c* the number of wales remains unchanged. From *c*—*c* to 30 *d*—*d* the fabric is narrowed to the number of loops required for the foot whereupon, if desired, an instep gusset may be formed.
- It will appear that the narrowing lines A—B—C—D extend on the same wale during the widening, the rounding and the narrowing of the heel, starting both from the upper rear end of the heel and extending at an inclined angle toward the ankle or below, like the narrowing lines of a pointed high heel as distinguished from the narrowing lines of pocket heels which extend about vertically from the ankle toward the sole.
- I wish it to be understood that I do not desire to be limited to the exact details of construction shown and described for obvious modifications will occur to a person skilled in the art.
- Various changes may be made in the details disclosed in the foregoing specification without departing from the invention or sacrificing the advantages thereof.
- I claim:
1. A stocking having a pair of widened rows of selvedge loops to be sewed at the widening of the heel, and narrowing lines beginning at the rear upper end of the heel and descending toward the ankle on the same wale at an inclined angle like those of a pointed high heel.
  2. A stocking having a pair of widened rows of selvedge loops to be sewed at the widening of the heel, and narrowing lines beginning at the rear upper end of the heel and descending to a point below the ankle on the same wale at an inclined angle like those of a pointed high heel.
3. The method of knitting stockings in a single operation on flat knitting machines, comprising widening the heel by widening the selvedge loops to be sewed, and at the same time transferring heel loops inwardly 70 the number of which increases with each row.
4. The method of knitting stockings in a single operation on flat knitting machines, comprising widening the heel by widening the selvedge loops to be sewed at one end of a given row, transferring loops inwardly at the other end of said row without involving the selvedge loops, and widening the selvedge loops at this other end of the row.
- In testimony whereof I affix my signature.
